UNITED STATES PATENT OFFICE.

WILLIAM C. HEIMERDINGER, OF LOUISVILLE, KENTUCKY.

MACHINE FOR SHARPENING RAZORS.

No. 839,289.

Specification of Letters Patent.

Patented Dec. 25, 1906.

Application filed December 7, 1905. Serial No. 290,761.

To all whom it may concern:

Be it known that I, WILLIAM C. HEIMERDINGER, a resident of Louisville, in the county of Jefferson and State of Kentucky, have invented certain new and useful Improvements in Machines for Sharpening Razors; and I do hereby declare the following to be a full, clear, and exact description of the invention, such as will enable others skilled in the art to 10 which it appertains to make and use the same.

My invention relates to improvements in a machine for sharpening razors, the object of the invention being to provide an improved razor-clamp so constructed that it will hold 15 all razors of standard make, regardless of size, with their cutting edge in the same plane to be properly presented to the rolls and provide improved means for feeding the razor back and forth and improved means for 20 shifting the razor from side to side and exerting varying pressure thereon.

With these and other objects in view the invention consists in certain novel features of construction and combinations and arrangements of parts, as will be more fully hereinafter described, and pointed out in the claims.

In the accompanying drawings, Figures 1 and 2 are views in cross-section, illustrating 30 my improvements. Fig. 3 is a view in elevation, and Figs. 4, 5, 6, and 7 are detail views, illustrating the blade-holder.

1 represents a table or frame providing mounting thereon for a horizontal shaft 2, on 35 which sharpening-rolls 3 3' are secured and provided on their opposite faces with leather, stone, or other material to strop, hone, or grind a blade, and, in fact, machines will be provided containing all the stones and hone 40 necessary to put the best possible edge on the razor, and it will be understood that when these rolls are hereinafter referred to as "sharpening-rolls" it is intended to cover all material for the purpose.

45 A lever 4 is fulcrumed at its lower end on a rod 5 and carries a frame 6 at its upper end, made with alined bearings for a shaft 7, located at right angles to lever 4, and to the inner end of this shaft my improved razor-clamp is secured and will be more fully hereinafter described.

The outer end of shaft 7 has a depending arm or plate 8 secured thereon, and the latter is made with a bifurcated lug 9 to receive a 55 long thin spring-bar 10, which latter extends through a slotted finger 11, adjustably se-

cured on an upright rod 12, carried by a horizontal reciprocating rod 13, mounted to slide in bearings in frame 1.

The frame 1 also supports a drive-shaft 14, having a drive-pulley thereon, and a belt 16 transmits motion from a pulley 17 on drive-shaft 14 to one member of a friction clutch-pulley 18 on a short shaft 19, and the other member 18^a of said friction clutch-pulley 18 is connected by a belt 20 with a pulley 21 on a short shaft 22. The friction clutch-pulley 18 is provided with an operating-bar 23, connected with any approved treadle mechanism to permit the member 18^a of clutch 18 to 65 be held to stop the movement of the razor.

Short shaft 22 is provided at one end with an adjustable crank-arm 24, connected by a link 25 with lever 4 to swing the latter back and forth and move the razor in and out 75 between the sharpening-rolls, which latter are continuously driven by a belt connecting a pulley 27 on the drive-shaft with a pulley 28 on shaft 2.

A belt 29 connects a pulley 30 on the drive-shaft with a pulley 31 on a worm-shaft 32, the worm on the latter shaft meshing with a worm-wheel 33 on a cross-shaft 34, which latter carries at its end an adjustable crank-arm 35, connected by a link 36 with a swinging lever 37, pivotally supported at its upper end and connected at its lower end to an arm 38 on the reciprocating bar 13.

My improved razor-clamp above referred to is constructed as follows: The razor-clamp 90 comprises a metal block 39, secured to the end of shaft 7 by a bolt 40 and nut, as shown, and is made with inclined sides to receive plates 41, secured thereto by screws or otherwise. The block 39 about midway its 95 length is made with an opening to receive a sliding pin 42, secured at its upper end to a bar 43, movable between plates 41 and adapted to press against the back of the razor-blade, and the block 39 is grooved to receive this bar 43 when in its lowest position. The lower end of pin 42 projects through an opening in an operating-lever 44 and has a cross-pin 45 below the same, so that when lever 44 is forced down the bar 43 will be 100 drawn down with it, and a wire spring 45^a, supported on the block 39, is connected at one end to pin 42 to exert upward pressure on bar 43 to force the razor up into proper position in the holder. As all razors of standard make have the same relative width of base in accordance with the width of the

blade to give the same angle of pitch to the blade when laid flat, and as the side plates of the clamp are located at this standard pitch, the edge of each and every standard razor 5 will be held by the clamp in precisely the same position, for if it be a narrow blade it will have a correspondingly narrow base and will be projected farther upward by the bar 43. The razors are slid between the side 10 plates of the clamp at one end, and said side plates may have clamping-fingers, as shown, or these fingers may be dispensed with, as desired.

The operation is as follows: The sharpening-rolls are turned continuously, and when a 15 razor is in the clamp and the clutch-pulley 18 permitted to operate lever 4 will be swung inward and outward to move the razor in and out between the rolls, and the rod 13 will be reciprocated by the mechanism above explained to tilt the razor from side to side. By employing the flexible spring-bar 10 it 20 will be seen that the blade will first, lightly touch one roll, and as the rod 13 continues to move and bow the spring-bar 10 pressure of the razor against the roll will be gradually increased until the maximum is reached, when the rod begins to move in the opposite direction, thereby gradually reducing the pressure 25 30 until the minimum and moving the razor over to engage the other roll, and so on, thus carrying out the correct operation of hand-sharpening with perfect and regular manipulation to produce the best possible edge.

35 Slight changes might be made in the general form and arrangement of the parts described without departing from my invention, and hence I do not restrict myself to the precise details set forth, but consider myself 40 at liberty to make such slight changes and alterations as fairly fall within the spirit and scope of my invention.

Having fully described my invention, what I claim as new, and desire to secure by Letters Patent, is—

45 1. In a sharpening-machine, the combination with two sharpening-rolls and a work-holder, of means operating to automatically reciprocate and oscillate the work-holder and 50 drive the sharpening-rolls.

55 2. The combination with two sharpening-rolls and means for rotating them simultaneously in the same direction, of a work-holder and means for reciprocating said work-holder between the sharpening-rolls and means operating to oscillate said reciprocating work-holder.

60 3. The combination with two sharpening-rolls, and means for rotating them, of a work-holder, means for reciprocating said work-holder, means for oscillating the work-holder, and a source of power for operating both of said means.

65 4. The combination with a sharpening-roll and means for rotating the same, of a

work-holder, and means for alternately reciprocating and oscillating said work-holder to move the work longitudinally relatively to the roll and then laterally away from the same. 70

5. The combination with a sharpening-roll, and means for rotating the same, of a pivoted arm or lever, an oscillatory work-holder carried by said arm or lever, means for oscillating the arm or lever to reciprocate 75 the work-holder relatively to the sharpening-roll, and means for oscillating the work-holder.

6. The combination with two sharpening-rolls, and means for rotating said rolls simultaneously, of a pivoted arm or lever, an oscillatory work-holder carried by said arm or lever, means for oscillating said arm or lever to reciprocate the work-holder between the sharpening-rolls, and means for oscillating 85 said work-holder. 80

7. In a machine of the character described, the combination with revolving rolls having facing sharpening-surfaces, of a razor-holder, means for reciprocating said holder 90 between the rolls, and means for tilting the holder from side to side.

8. In a machine of the character described, the combination with two rolls having facing sharpening-surfaces and means 95 for rotating said rolls, of an oscillatory razor-holder, means for reciprocating said holder between the rolls, and elastic means for oscillating the holder to present the faces of the razor to both rolls with varying degrees of 100 pressure.

9. The combination with a sharpening-roll and means for rotating it, of an oscillatory work-holder, means for reciprocating the work-holder relatively to the roll, a 105 spring connected with the oscillatory work-holder, and means for operating said spring to oscillate the work-holder.

10. The combination with sharpening-rolls and means for rotating them, of an oscillatory work-holder, means for reciprocating said work-holder between the rolls, and operating means for oscillating the work-holder, said operating means including a 110 spring. 115

11. The combination with sharpening-rolls, and means for rotating the same, of an oscillatory work-holder, means for cushioning the oscillatory movements of holder, and means for reciprocating said oscillatory 120 holder between the sharpening-rolls.

12. In a machine of the character described, the combination with revolving rolls having facing sharpening-surfaces, of a swinging lever, a shaft carried by the lever, a 125 razor-clamp carried by the shaft, to move between the rolls, a depending arm on said shaft, a flexible spring-bar secured to the arm, and means for swinging the lower end of the spring-bar to turn the shaft and move 130

the razor-clamp to present the razor to both rolls with varying degrees of pressure.

13. In a machine of the character described, the combination with continuously-revolving rolls having facing sharpening-surfaces, of a swinging lever, a shaft carried thereby, a razor-clamp carried by the inner end of the shaft, means for swinging the lever to move the clamp back and forth between the rolls, a depending spring-bar connected with the outer end of the shaft, a reciprocating rod, an arm thereon, and a slotted finger on the arm to receive the spring-bar.

14. A razor-clamp for a sharpening-machine, comprising a block having inclined sides, plates secured to the sides and disposed at the proper angle to project the edges of all standard razors an equal distance from the edges of said plates, and a spring-pressed bar between said plates.

15. A razor-clamp for a sharpening-ma-

chine, comprising a block having beveled sides, plates secured to the sides of the block, a bar between the plates, a pin secured to the bar and projecting through an opening in the block, a spring exerting upward pressure on the pin, and a lever fulcrumed at one end and connected between its ends to said pin.

16. In an automatic razor-sharpening machine, the combination with two rolls having sharpening-surfaces facing each other, of a swinging razor-holder to move back and forth between the rolls, and automatic elastic mechanism for tilting the holder from side to side and varying the pressure thereon.

In testimony whereof I have signed this specification in the presence of two subscribing witnesses.

WILLIAM C. HEIMERDINGER.
